UNITED STATES PATENT OFFICE.

CARL BIEDERMANN, OF LUCERNE, SWITZERLAND.

ENVELOPE.

Application filed April 27, 1923. Serial No. 635,158.

The commonly used envelopes are generally made of paper and only those designed for storing valuables are made of canvas. Envelopes of the former type can be used only once whereby the expenses of bigger firms are considerably increased.

This invention relates to an envelope which differs from envelopes of known construction by the fact that it can be used repeatedly and that the contents of the same are well protected against being creased and against unlawful removal. This object is attained by making the envelopes from aluminium foil and with an open side closed by a removable element.

Three embodiments of the invention are shown by way of example on the accompanying drawing, wherein:

Fig. 1 shows in elevation a window-envelope.

Fig. 2 is a section on line I—II of Fig. 1, showing the preferred form of construction.

Fig. 3 shows in front elevation, and

Fig. 4 shows in rear view an envelope of the second form of construction.

Fig. 5 is a side elevation, and

Fig. 6 is a section on line II—III of Fig. 5 showing a third form of construction.

According to the first form of construction (Figs. 1 and 2) the envelope consists of a sheet of aluminium foil folded to form a pocket having a front wall 1 and a rear wall 2. The front wall 1 has at both sides flaps 3 which are folded over and rigidly fixed on the rear wall, for instance by pressing or denting. The front wall and the rear wall have each slits 4 in proximity to the upper open side of the envelope through which slits passes the tape 5. This tape 5 is of paper and its ends are glued together on the back of the envelope. The front wall has a transparent window as usual through which the address can be read which is written on the letter enclosed in the envelope. The window 6 consists of an aperture which may be closed by transparent paper.

To open the envelope the paper tape 5 is simply destroyed and for sealing an envelope a tape is inserted through the slits 4 the ends of the tape being glued together on the back of the envelope.

In the envelope of the second form of construction shown in Figs. 3 and 4 the front wall 1 and the rear wall 2 are also made from a sheet of aluminium foil. At the side edges of the front wall flaps 3 are arranged which are folded and stuck on the rear wall. Narrow strips 7 stamped out of the front wall of the envelope are inserted through slits 8 of the rear wall. Through the loops 60 7 the ends 9 of the paper strip 10 are inserted, said ends 9 being glued together so that the envelope is securely sealed. The address of the receiver is written on the front side of the paper strip 10, the address 65 of the sender being written on the rear side of the strip. Addresses which are frequently used may be printed on these bands 9.

The envelope of the third form of construction shown in Figs 5 and 6 differs from those which have been described above in that the envelope is designed to be used for the safe keeping of documents. The envelope of aluminium foil composed of a front wall 1 and rear wall 2 connected by flaps 3 has near its upper open edge several holes 11 arranged at convenient distances apart through which a string 12 is twined. The ends of the string 12 are securely connected 75 80 by a seal 13 so that it is impossible to open the envelope without destroying the seal or cutting the string.

At the open edge of the envelope flaps could further be arranged which have to be securely connected one with the other by lead seals whereby the safety of the envelope is increased. In this case the envelope could be used only once as it would be impossible to remove the lead seal without destroying the flaps.

The aluminium foil is 0,1 to 0,4 millimeter thick and it is to be expected that owing to the advantages realized the envelopes of this type will be frequently used.

The connection of the front wall and back wall could evidently be effected also in any other convenient manner as described.

Envelopes to be used for printed matter and commercial papers are preferably made, 100 as is actually the case, with a flap on the upper edge of the front wall.

I claim:—

An envelope for repeated use comprising in combination a pocket of aluminium foil open at the top end having a window at a 5 convenient point of the front wall through which the address written on the enclosure can be read and vertical slits near the top

edges of the rear and front walls, and a paper band to be passed through said slits, and the ends of said paper band to be connected on the rear of the envelope by sealing.

10

In testimony whereof I affix my signature.

CARL BIEDERMANN.
